UNITED STATES PATENT OFFICE

SIDNEY B. BLAISDELL, OF WYNCOTE, PENNSYLVANIA, ASSIGNOR TO FIDELITY MACHINE COMPANY, OF WILMINGTON, DELAWARE, A CORPORATION OF DELAWARE

BRAIDING MACHINE

Application filed November 5, 1929. Serial No. 405,038.

This invention relates to braiding machines, and particularly to those employing a large number of individual threads, for example, machines having approximately thirty-six ends.

Prior to my invention it has been the practice, in order to use bobbins of such a size that it would not be necessary to stop the machine too frequently to replenish the bobbins, to make the bobbin-supporting platform of a tremendously large diameter, it being understood by those familiar with the art that the diameter of the bobbins is governed by the amount of clearance existing between any two of the bobbin carriers as they pass in opposite directions around undulated and intertwining paths defined by guiding grooves or slots formed in the bobbin-supporting platform; and that to increase this clearance to permit of the use of larger bobbins and in order to use the large number of bobbins the paths are necessarily expanded, which necessitates the use of the extremely large bobbin-supporting platform above noted.

It is also understood by those familiar with the art that the maximum lineal speed at which the carriers can be safely operated to avoid ballooning and tangling of the threads has been definitely established.

Machines of this type are subject to many disadvantages, which, collectively, materially decrease the daily production of the large machine as compared with a smaller machine employing half the number of threads, or less. For example, the greater length of the paths traveled by the carriers moving at maximum lineal speed requires a greater length of time for each carrier to complete one full circuit around the platform; the large diameter of the bobbin-supporting platform makes it more difficult and requires more time for the operator to tie up broken ends and to perform other necessary duties at and near the center of the machine; the large supporting platform also requires more floor space to accommodate the machine; and further, these machines, enlarged to the greatest possible extent and using bobbins of the greatest possible diameter under the circumstances, must

be stopped on the average of three times during a normal working day to replenish the bobbins on the carriers and each of these bobbin changing stoppages entails a loss of approximately thirty minutes of the otherwise available producing time of the machine.

The principal object of my invention is to increase the production of braiding machines employing a large number of ends. This object I accomplish primarily by dividing the number of bobbins into two separate series and by providing a separate platform for each series, the platforms being superposed above each other and so arranged that the threads of the lower series pass through the platform supporting the upper series, the two series of threads being manipulated with respect to each other to effect the braiding operation in the same general manner as in the large machine.

The use of two platforms reduces the diameters thereof so that the paths traveled by the carriers are shortened in length and, therefore, require less time for the carriers to travel through a complete circuit around the platform at the maximum speed, which materially increases the daily production of the machine.

The use of two platforms reduces their diameters to such an extent that the operator can more readily perform the necessary duties at and near the center of the machine, which adds to the increased production.

The use of two platforms of reduced diameters placed one above the other materially reduces the floor space required to accommodate the machine.

The use of two platforms also permits the use of bobbins of such an increased size, as compared to those used in the large single deck machine, that the machine need be stopped but once in a normal working day to replenish the bobbins, thus adding practically one full hour to the actual producing day of each machine.

A machine made in accordance with the principles of my invention in practice has proven that it requires so little attention from the operator that a single operator can very readily tend three or more machines, as

compared to one of the large machines above noted, thereby producing a large saving in wages to the manufacturer.

In the accompanying drawings, I have illustrated a machine for producing tubular braiding, such as is used for covering rubber hose, electric cable, and similar merchandise wherein the braiding is effected around a suitable core, such as a rubber hose or cable would provide.

The construction and operation of my improved machine will be fully disclosed hereinafter, reference being had to the accompanying drawings, of which:

15 Fig. 1 is a side elevation;

Fig. 2 is a sectional elevation taken on the line 2—2, Fig. 1;

Fig. 3 is a sectional plan view taken on the line 3—3, Fig. 1;

20 Fig. 4 is a sectional plan view taken on the line 4—4, Fig. 1;

Fig. 5 is a sectional plan view taken on the line 5—5, Fig. 1;

25 Fig. 6 is a sectional plan view taken on the line 6—6, Fig. 1;

Fig. 7 is a side elevation of one of the bobbin carriers, removed from the machine; and

30 Fig. 8 is a side elevation of one of the independent thread guides employed in my improved machine.

As shown in Figs. 1 and 2, the machine comprises a main base plate or lower deck 1, which is supported at a suitable distance above the floor by suitable legs 2, 2. An aperture 3 is provided at the center of the base plate 1, and a vertically extending hollow column 4 passes through this opening and is secured to the underside of the base plate 1 by means of screws or bolts 5, which pass through a circular flange 6 formed integral with the lower end of the hollow column 4 which forms a part of the lower deck 1, as illustrated in Fig. 2.

The upper end of the hollow column 4 is 45 provided with a circular shoulder 7 on which rests the lower end of a hub 8 formed integral with a deck plate 9 which constitutes the central section of an upper deck 10, the section 9 thereof being held against rotary movement 50 relative to the column 4 by means of suitable keys 11, 11. In addition to the central section 9, the upper deck 10 comprises an outer section 12 which is supported from the lower deck 1 by means of vertically extending posts 55 13, 13.

Between the outer edge of the central section 9 and the inner edge of the outer section 12 of the upper deck 10 is formed an undulated slot 14, for purposes hereinafter set forth.

Spaced above the upper deck 10 is a bobbin carrier supporting platform 15, which comprises an outer section 16, an inner section 17 and a plurality of intermediate sections 18, the adjacent edges of said sections combining

to form a pair of undulated slots 19 and 20. The sections 16 and 17 of the platform 15 are rigidly supported by posts 21, 21, and the intermediate sections 18 are supported by posts 22, extending vertically from and secured to the upper deck 10. As shown in Fig. 4, the platform 15 is open at its center as indicated at 23.

The undulated slot 19 forms a guideway for a series of combined thread guiding elements 75 and bobbin carriers 25, one of which is shown in detail in Fig. 7.

Each of the thread guiding elements 25 comprises a foot 26 which is adapted to rest on the upper surface of the platform 15. Depending from the foot 26 is an elongated fin 27 which extends through the slot 19, the opposite ends of said fin being beveled as illustrated in Fig. 4. At the lower end of the fin 27 and spaced from the foot 26 a distance substantially equal to the thickness of the platform 15 is a guide-plate 28, which bears against the underside of the said platform and thereby operatively maintains the bobbin carrier in an operating position on and relative to the stationary platform 15. Depending from the underside of the guide plate 28 is a stud 29, for purposes hereinafter described.

Formed integrally with and projecting vertically from the foot 26 in the present instance is the thread guide in the form of a post 30 having openings 31 and 32 for a thread α as it passes from the bobbin B carried by the element 25 to the braiding point of the machine.

The bobbin B is adapted to be placed on and frictionally engage a core element 33, which is rotatably mounted on a vertically extending spindle 34 projecting vertically from the foot 26. The core element 33 is provided with a flange 35, the peripheral edge of which is toothed for engagement by one end of a pawl element 36 which is pivotally mounted at its center 37 to the spindle 34, the core element 33 being supported on the spindle 34 by means of a collar 38 formed integral with or secured to the said spindle. A spring 39 is provided between the collar 38 and one end of the pawl element 36 and tends to maintain the said end of the pawl in engagement with the toothed edge of the flange 35 at all times.

Attached at 40 to the opposite end of the pawl element 36 is one end of a link 41, the opposite end of which is in the form of a loop 42 passing around and slidably carried by the thread guide post 30 at a point intermediate the openings 31 and 32 therein.

Below the loop 42 on the post 30 is slidably mounted a tension weight 43, under the lower edge of which the thread α passes, as it is drawn from the bobbin B, through the opening 31 and the opening 32 to the braiding point of the machine, and when the 130

thread α becomes taut the tension weight 43 is raised and engages the loop 42 which, through the link 41, turns the pawl 36 on its pivot 37 against the action of the spring 39 and thereby releases the bobbin B, permitting it to rotate on the spindle 34 and thereby pay out the thread α . When sufficient of the said thread α is drawn from the bobbin by the weight 43 the said weight will drop to a position permitting the pawl 36 to again engage the toothed flange 35 of the bobbin core 33, and thereby arrest the bobbin B.

The undulated slot 20 forms a similar guideway for a series of independent thread guiding elements 45, one of which is shown in detail in Fig. 8. Each of the thread guiding elements 45 comprises a foot 46 having a depending and beveled-ended fin 47 at the lower end of which is formed a guide plate 48 which maintains the thread guide in operative position on the platform 15. Depending from the plate 28 is a hollow stud 49.

Extending vertically from the upper side 25 of the foot 46 is a thread guide tube 50, the bore 52 of which is in vertical alignment with the bore 51 of the hollow stud 49, the said tube 50 being suitably secured in a boss 53 formed on the upper side of the foot 46. 30 As shown in Figs. 1 and 2, the upper ends of the thread guiding posts 30 and the upper ends of the thread guiding tubes 50, of the thread guiding elements 25 and 45 respectively, are in substantially the same horizontal plane spaced above the stationary platform 15.

As shown in Fig. 4, the undulated slots 19 and 20 cross each other at points intermediate the extreme outer and inner curves 40 thereof, it being understood that the series of thread guiding elements 25 will travel in the slot or guideway 19 in the direction of the arrow a , while the thread guiding elements 45 will travel in the undulated slot 45 or guideway 20, and in the direction of the arrow b , opposite to the direction of travel of the thread guiding elements 25, as shown in Fig. 4.

The undulated slot 14 in the upper deck 50 coincides vertically with the undulated slot 20 formed in the platform 15, which is located above the said upper deck 10; and the hollow studs 49 of the thread guiding elements 45 extend through the said slot 14 in the upper deck 10 to a point below the lower surface of the upper deck 10, as clearly illustrated in Fig. 2.

Rotatably mounted on the central column 4 and vertically supported by that part of the 55 lower deck 1 which is formed by the flange 6 of the said central column 4, is a rotary movable platform 55, which is adapted to support a series of bobbin carriers 65. These bobbin carriers 65 are of the same construction as the bobbin carriers of the thread guid-

ing elements 25, with the exception that they are not provided with the depending fins 27, the guide plates 28, or the studs 29, and in place of being separately movable over their supporting platform the bobbin carriers 65 70 are rigidly secured in spaced relation to each other on the rotatable supporting platform 55, by means of screws 57 which pass through the foot plates 56 of the bobbin carriers 65, as illustrated clearly in Fig. 6.

This rotary platform 55 is adapted to move and carry the bobbin carriers 65 in the same general direction as the series of independent thread guiding elements 45, as indicated by the arrow c in Fig. 6.

The annular cavity formed in the lower deck 1 between the inner edge of the opening 3 and the outer surface of the column 4, forms an oil well in the said lower deck in which the hub of the rotary platform 55 operates at all times and is thereby kept well lubricated.

The number of bobbin carriers 65 carried by the rotary platform 55 is the same as the number of independent thread guiding elements 45 mounted on the rigid supporting platform 15; and each of the said bobbin carriers 65 is adapted to supply a thread α^1 90 from its bobbin B¹ to the corresponding independent thread guiding element 45, which is located substantially in a direct line 95 above the respective bobbin carrier 65.

Each of these bobbin carriers 65 is provided with a tension weight 43^a mounted on the thread guiding post 30^a which is provided with an upper thread eye 32^a the same as the posts 30 of the thread guiding elements 25 illustrated in Fig. 7, the bobbin carriers 65 being provided with a bobbin-controlling pawl 36^a under control of the said tension weight 43^a.

While any given one of the independent thread guiding elements 45 is making a complete circuit of its guideway or undulated slot 20 on the upper deck 10, the corresponding bobbin carrier 65 is also making one complete circle on the lower deck 1 in accordance therewith, so that the said bobbin carrier 65 will at all times be in position to feed the thread α^1 directly to the bore 51 of the hollow stud 49 of its corresponding thread guiding element 45.

The bobbin carrying thread guiding elements 25 and the independent thread guiding elements 45 mounted on the rigid supporting platform 15 are moved over the surface of the said platform 15 of the upper deck 10 by means of a train of intermeshing gears 70 which are provided with a plurality of pairs of spaced horns 71. The respective pairs of horns 71 are adapted to engage the studs 29 and 49 of the thread guiding elements 25 and 45 respectively, and in the same general manner as is common to ordinary braiding machines.

As shown in Fig. 5, the periphery of each of the gears 70 is notched or cut out as indicated at 72, said notch extending radially inward from the periphery of the gear toward the center thereof to accommodate the hollow studs 49 of the thread guiding elements 45 in their passage from the stationary platform 15 to the lower side of the upper deck 10.

As shown in Fig. 5, these notches 72 are provided between the horns 71 of two pairs which are disposed diametrically opposite to each other on the gears 70, no notches being provided between the horns of the other diametrically opposed pairs of horns disposed at 90° with respect to the first said pair having the notches for the reason that the studs 29 of the thread guiding elements 25 do not extend to a point below the upper surface of the said gear 70, on which the said horns are formed.

As these gears 70 are rotated the horns 71 thereon will engage the said studs 29 and 49 and thereby convey the respective thread guiding elements through the curved portions of the undulations of the guideways 19 and 20 with which each of these gears is axially aligned, the crossing of the said undulated guideways 19 and 20 transferring the studs of the respective thread guiding elements from the embrace of the horns of one gear into the embrace of the horns of the next adjacent and intermeshing gear, in the manner common to braiding machine operation.

The train of gears 70 is driven through a pair of intermediate pinions 73, 73 meshing with one of the said gears 70 and with a gear 74 which is secured to a vertical shaft 75. The gears 70 are rotatably mounted on the posts 22 which support the intermediate sections 18 of the stationary platform 15, from and above the upper deck 10.

The lower end of the shaft 75 is rotatably mounted in a bearing 76 formed on a bracket 77 which is rigidly secured to the lower deck 1 by means of bolts 78, as clearly illustrated in Fig. 1, and the upper end of the said shaft 75 is mounted in a bearing 79 formed on the outer end of an arm 80, the opposite end of which is provided with a hub 81 rigidly secured to a vertically extending post 82, which is secured at its lower end to the outer section 12 of the upper deck 10. The shaft 75 is also supported, adjacent the gear 74, in a bearing 84 formed integral with and projecting from the outer section 12 of the upper deck 2.

The peripheral edge of the rotary platform 55 is provided with gear teeth 85 adapted to mesh with the teeth of a gear 86 which is secured to the shaft 75 adjacent the lower deck 1.

Loosely mounted on the shaft 75, below the gear 86, is a beveled gear 87, which meshes with a beveled gear 88 secured to one

end of a shaft 89 rotatably mounted in a bearing 90 formed integral with the bracket 77, a suitable drive pulley 91 being secured to the opposite end of the shaft 89, by means of which power is applied to the machine 70 from any suitable source.

The underside of the beveled gear 87 is provided with clutch teeth 92 which are adapted to be engaged by similar teeth 93 formed on the upper end of a clutch sleeve 94, which is splined to the shaft 75 intermediate the beveled gear 87 and the gearing 76. The clutch sleeve 94 is adapted to be controlled by a lever 95 fulcrumed at 96 in the bracket 77.

Pivottally connected at 98 to the clutch lever 95 is a latch 99 which projects vertically above the movable platform 55 and is there provided with a shoulder 100 which is adapted to rest on the upper side of a horizontally disposed latch lever 101. This lever 101 is secured to a vertically disposed shaft 102 rotatably mounted at its opposite ends in the lower deck 1 and the upper deck 10 respectively. Above the stationary platform 15, the shaft 102 is provided with a second arm 101^a corresponding to the above mentioned arm or lever 101.

If any of the threads x or x^1 should break during the operation of the machine, the tension weights 43 or 43^a, as the case may be, which is controlled by the broken thread, will immediately drop to a point adjacent the foot 26 or 46 and as the machine continues to operate the tension weight lying in this lower position will strike one or the other of these levers 101 and 101^a, depending upon whether the broken thread is coming from a bobbin on the upper or the lower deck, causing the shaft 102 to be rotated and the latch lever 101 moved from under the shoulder 100 of the latch 99, which will permit the said latch 99 and the clutch lever 95 to drop, thereby permitting the clutch sleeve 94 to slide axially on the shaft 75, disconnecting the teeth 93 of the said sleeve from the teeth 92 of the beveled gear 87, and thereby stopping the machine.

As shown in Fig. 2, a core element Z, such as a rubber hose, electric cable, or the like, passes up through the hollow column 4 and through the central opening 23 in the upper stationary bobbin-supporting platform 15, through a suitable mandrel 105 and around a take-up wheel 106.

The take-up wheel 106 is rotatably mounted on a horizontally disposed shaft 107 mounted in brackets 108 which in turn are mounted on the upper ends of the post 82 and a corresponding post 82^a which, like the post 82, is secured to and projects vertically from the upper deck 10.

Secured to the take-up wheel 106 is a gear wheel 109 which meshes with a gear 110 secured to one end of a horizontally disposed

shaft 111, one end of which is rotatably mounted in the arm 80 and the opposite end of which is rotatably mounted at a suitable bearing 112.

5 Adjacent the arm 80, the shaft 111 is provided with a gear 113 which meshes with a gear 114 secured to one end of a short shaft 115, on the opposite end of which is secured a worm wheel 116, which meshes with a worm 117 secured to the vertical shaft 75. The shaft 115 is rotatably mounted in a bearing formed in the lower end of an arm 118 depending from the arm 80. The bearing 112 and the mandrel 105 are secured to a horizontally disposed arm 120 which is secured to a horizontally disposed rod 121 carried in brackets 122 and 122^a secured to the posts 82 and 82^a respectively. The arm 120 is steadied by a third post 123 secured to and projecting vertically from the upper deck 10.

20 The mandrel 105 in the present instance consists merely of a plate having an opening of sufficient diameter to permit the core element Z to pass freely therethrough, and acts as a means for supporting the core element at or immediately adjacent the braiding point in the machine.

25 Upon referring to Fig. 3, it will be obvious that the bobbins B carried by the group of thread guiding elements 25 may be of the proportion indicated at B² permitting a clearance indicated at C which need be only of a sufficient width to permit the passage between the peripheries of the adjacent 30 bobbins of the thread guide tube 50 of one of the independent thread guiding elements 45.

35 The diameter of a full bobbin, as indicated at B², is materially greater than the maximum 40 sized bobbins capable of being used in the large type machines described in the preamble of the specification, and due to the fact that only one-half of the total number of bobbins working in the machine at one time are located on any single one of the supporting 45 platforms the path followed by these bobbins can be materially contracted toward the center of the machine, thus producing a machine which requires considerably less floor space 50 than do machines of the type above noted, and the corresponding decrease in the overall dimensions of the machine will permit the operator to perform his duties quicker and more efficiently.

55 A machine constructed in accordance with the principles of my invention as above described is capable of increasing the production of a single machine approximately fifty 60 per cent and still maintain the maximum safe lineal speed of the thread guiding elements, for the reason that the distance traveled in making a complete circuit of one of the undulated guideways 19 or 20 is proportionately less than the distance around one

of the guideways of the large machines above noted.

In my improved machine the radius of each of the curves of the undulated guideways is less than in the machines of the prior art, and due to the fact that but one set of bobbins is located on each deck of the machine the size of the bobbins is increased about forty per cent. For example, the bobbins of large machines of the prior art as above described use 70 bobbins substantially three inches in diameter and about six inches long, whereas, in a machine made in accordance with the principles of my invention I may use a bobbin about four inches in diameter and about eight 75 inches long, which increases the volume of thread about three times that of the smaller size bobbin.

80 While the details of construction of a machine made in accordance with the principles of my invention are subject to considerable modification, within the scope of the invention, the fundamental principles involved, that is, dividing the total number of bobbin carriers into separate groups and locating 85 each group in a position remotely situated with respect to another group, with all the groups of bobbin carriers respectively supplying threads to different groups of thread guiding elements located and operating in a single plane common to all, is an innovation 90 in the braiding art, and it is this principle and the general construction of the machine on which I wish to secure Letters Patent.

95 While I have described my invention as being especially adapted for machines using a larger number of ends, for example, thirty-six, it will be obvious that the machine is equally adaptable for use with any desired number of ends without departing from the 100 essential features of the invention.

105 I claim:

110 1. A braiding machine comprising a pair of superposed decks; a platform spaced above and rigidly secured to the upper deck of the machine, said platform having a pair of undulated and intertwining slots formed therein; a group of bobbin carriers respectively provided with thread guiding elements, mounted on the stationary platform and movable in one direction along one of said slots 115 therein; a group of independent thread guides mounted on the said stationary platform in alternate relation to the said bobbin carriers and movable in the other of said slots in a 120 direction opposite to the direction of movement of said bobbin carriers; a platform rotatably mounted on the lower deck of the machine and movable in the same general direction as the said group of independent thread guides; a plurality of bobbin carriers rigidly mounted on said rotary platform and adapted to supply thread to the said independent 125 thread guides respectively; a tension weight slidably mounted for vertical movement on 130

- each bobbin carrier on both the upper and lower decks; a trip shaft extending vertically between said upper and lower decks; a trip arm on said trip shaft at the upper deck; and a trip arm on said trip shaft at the lower deck, said tension weights being adapted to engage said trip arms to actuate said trip shaft for stopping the machine when any of the threads on either deck fails to maintain a predetermined tension.

2. A braiding machine comprising a pair of superposed decks; a platform spaced above and rigidly secured to the upper deck of the machine, said platform having a pair of undulated and intertwining slots formed therein and extending completely therethrough; a group of bobbin carriers respectively provided with thread guiding elements, mounted on the stationary platform and movable in one direction along one of said slots therein; a group of independent thread guides mounted on the said stationary platform in alternate relation to the said bobbin carriers and movable in the other of said slots in a direction opposite to the direction of movement of said bobbin carriers; a platform rotatably mounted on the lower deck of the machine and movable in the same general direction as the said group of independent thread guides; a plurality of bobbin carriers rigidly mounted on said rotary platform and adapted to supply thread to the said independent thread guides respectively, a train of intermeshing gears intermediate the upper deck and the stationary platform; a stud on each of the bobbin carriers and independent thread guides located on the said stationary platform said studs extending through and below the stationary platform; and horns on said gears adapted to engage said studs below the stationary platform to move the said thread guides and bobbin carriers along path defined by the said undulated slots in the platform, the studs of said independent thread guides extending through notches formed in the peripheries of said gears and through an undulated slot formed in the said upper deck to a point below said upper deck.

3. A braiding machine comprising a pair of superposed decks; a platform spaced above and rigidly secured to the upper deck of the machine, said platform having a pair of undulated and intertwining slots formed therein and extending completely therethrough; a group of bobbin carriers respectively provided with thread guiding elements, mounted on the stationary platform and movable in one direction along one of said slots therein; a group of independent thread guides mounted on the said stationary platform in alternate relation to the said bobbin carriers and movable in the other of said slots in a direction opposite to the direction of movement of said bobbin carriers; a platform rotatably mounted on the lower deck of the machine and movable in the same general direction as the said group of independent thread guides; a plurality of bobbin carriers rigidly mounted on said rotary platform and adapted to supply thread to the said independent thread guides respectively, a train of intermeshing gears intermediate the upper deck and the stationary platform; a stud on each of the bobbin carriers and independent thread guides located on the said stationary platform said studs extending through and below the stationary platform; and horns on said gears adapted to engage said studs below the stationary platform to move the said thread guides and bobbin carriers along paths defined by the said undulated slots in the platform.

4. A braiding machine comprising a pair of superposed decks; a platform spaced above and rigidly secured to the upper deck of the machine, said platform having a pair of undulated and intertwining slots formed therein and extending completely therethrough; a group of bobbin carriers respectively provided with thread guiding elements, mounted on the stationary platform and movable in one direction along one of said slots therein; a group of independent thread guides mounted on the said stationary platform in alternate relation to the said bobbin carriers and movable in the other of said slots in a direction opposite to the direction of movement of said bobbin carriers; a platform rotatably mounted on the lower deck of the machine and movable in the same general direction as the said group of independent thread guides; a plurality of bobbin carriers rigidly mounted on said rotary platform and adapted to supply thread to the said independent thread guides respectively, a train of intermeshing gears intermediate the upper deck and the stationary platform; a stud on each of the bobbin carriers and independent thread guides located on the said stationary platform said studs extending through and below the stationary platform; and horns on said gears adapted to engage said studs below the stationary platform to move the said thread guides and bobbin carriers along path defined by the said undulated slots in the platform, the studs of said independent thread guides extending through notches formed in the peripheries of said gears and through an undulated slot formed in the said upper deck to a point below said upper deck, the said studs of the independent thread guides and the said independent thread guides being hollow to permit of the passage of the threads from the bobbin carriers located on the lower deck.

5. A braiding machine comprising a pair of superposed decks, means for supporting the upper deck including a centrally disposed hollow column extending from the lower deck

- to the upper deck, a stationary platform on the upper deck and having a pair of undulated and intertwining slots formed therein about the axis of the said central column, a group of bobbin carriers respectively provided with thread guides mounted on said platform and adapted to move in a general direction along the path defined by one of the said slots, a group of independent thread guides mounted on said platform in alternate relation to the bobbin carriers thereon and adapted to move in a general direction opposite to that of the bobbin carriers along a path defined by the other of said slots, a platform rotatably mounted on the lower deck and adapted to rotate about the axis of said central column, a group of bobbin carriers rigidly secured to said rotary platform and adapted to supply threads to the independent thread guides located on the stationary platform of the upper deck, means for moving the bobbin carriers and the independent thread guides on the upper deck along their respective undulated paths about a core member extending through the said hollow central column to form a braided covering about said core member, and means for rotating the said rotary platform so that the bobbin carriers carried thereby will move in synchronism with the said independent thread guides on the upper deck.
6. A braiding machine comprising a pair of superposed decks; a platform spaced above and rigidly secured to the upper deck of the machine, said platform having a pair of undulated and intertwining slots formed therein and extending completely therethrough; a group of bobbin carriers respectively provided with thread guiding elements and mounted on the stationary platform for movement in one direction along one of the slots therein; a group of independent thread guides mounted on the stationary platform in alternate relation to said bobbin carrier and movable in the other of said slots in a direction opposite to the direction of movement of said bobbin carriers; a hollow standard extending between and secured to the upper and lower decks respectively to receive and deliver a core member at the axis of movement of the thread guides and bobbin carriers on the stationary platform; a platform rotatably mounted on said standard above the lower deck of the machine and movable in the same general direction as the group of independent thread guides on the stationary platform; a train of intermeshing gears intermediate the upper deck and the stationary platform for driving said rotary platform in synchronism with the group of independent thread guides on the stationary platform.
8. A braiding machine comprising a pair of superposed decks; a platform spaced above and rigidly secured to the upper deck of the machine, said platform having a pair of undulated and intertwining slots formed therein; a group of bobbin carriers respectively provided with thread guiding elements, mounted on the stationary platform and movable in one direction along one of said slots therein; a group of independent thread guides mounted on the said stationary platform in alternate relation to the said bobbin carriers and movable in the other of said slots in a direction opposite to the direction of movement of said bobbin carriers; a platform rotatably mounted on the lower deck for driv-
- ing said gear train; and a gear on said shaft adjacent the lower deck and engaging teeth formed on the periphery of the rotary platform for driving the rotary platform in synchronism with the independent thread guides on the stationary platform.
7. A braiding machine comprising a pair of superposed decks; a platform spaced above and rigidly secured to the upper deck of the machine, said platform having a pair of undulated and intertwining slots formed therein and extending completely therethrough; a group of bobbin carriers respectively provided with thread guiding elements, mounted on the stationary platform and movable in one direction along one of said slots therein; a group of independent thread guides mounted on the said stationary platform in alternate relation to the said bobbin carriers and movable in the other of said slots in a direction opposite to the direction of movement of said bobbin carriers; a platform rotatably mounted on the lower deck of the machine and movable in the same general direction as the said group of independent thread guides; a plurality of bobbin carriers rigidly mounted on said rotary platform and adapted to supply thread to the said independent thread guides respectively, a train of intermeshing gears intermediate the upper deck and the stationary platform; a stud on each of the bobbin carriers and independent thread guides located on the said stationary platform, said studs extending through and below the stationary platform; horns on said gears adapted to engage said studs below the stationary platform to move the said thread guides and bobbin carriers along paths defined by the said undulated slots in the platform; a vertical shaft extending between and rotatably mounted on the upper and lower decks, a gear on said shaft adjacent said upper deck driving said gear train; and a gear on said shaft adjacent the lower deck and engaging teeth on the periphery of the said rotary platform for driving said rotary platform in synchronism with the group of independent thread guides on the stationary platform.

deck of the machine and movable in the same general direction as the said group of independent thread guides; a plurality of bobbin carriers rigidly mounted on said rotary platform and adapted to supply thread to the said independent thread guides respectively; a tension weight slidably mounted for vertical movement on each bobbin carrier on both the upper and lower decks; a trip shaft extending vertically between said upper and lower decks; a trip arm on said trip shaft at the upper deck; a trip arm on said trip shaft at the lower deck, said tension weights being adapted to engage said trip arms to actuate said trip shaft for stopping the machine when any of the threads on either deck fails to maintain a predetermined tension; a vertical shaft extending between and rotatably mounted on the upper and lower decks, a gear on said shaft adjacent said upper deck driving said gear train; a gear on said shaft adjacent the lower deck and driving said rotary platform by intermeshing with teeth formed on the periphery thereof; a clutch on said vertical drive shaft; and means operatively connecting said clutch and the said trip shaft whereby the clutch is released when the drive shaft is operated.
